UNITED STATES PATENT OFFICE.

HENRY SPURRIER, JR., OF ST. ANNES-ON-THE-SEA, ENGLAND.

TRACTION-WHEEL.

SPECIFICATION forming part of Letters Patent No. 738,369, dated September 8, 1903.

Application filed October 17, 1902. Serial No. 127,725. (No model.)

To all whom it may concern:

Be it known that I, HENRY SPURRIER, Jr., a subject of the King of Great Britain and Ireland, residing at St. Annes-on-the-Sea, in the county of Lancaster, England, have invented new and useful Improvements in the Driving-Wheels of Self-Propelled Road-Vehicles, of which the following is a specification.

This invention relates to the driving-wheels of self-propelled road-vehicles; and its object is to provide means whereby projections may be temporarily produced in the rims of the wheels enabling them to obtain a grip upon slippery surfaces as and when required. It has already been attempted to provide temporary projections for the same purpose upon the driving-wheels in the form of cogs or spikes, which can be screwed into the rims of the wheels when required and be afterward removed therefrom; but it has been found that when the cogs are removed the holes in the rims become filled up and that the screw-threads therein become so blurred and battered that the cogs cannot again be inserted when required. My invention avoids this and other difficulties.

I will describe my present improvements with reference to the accompanying drawings, in which—

30 Figure 1 represents in elevation, and Fig. 2 in sectional side view, a part of a wheel with my means for producing the temporary projections applied thereto. Figs. 3 and 4 are views corresponding with Figs. 1 and 2 and show a modification in construction.

As illustrated by Figs. 1 and 2, I form internally-screw-threaded holes *a* through the rim *f* and felly *r* of each driving-wheel of the vehicle and fit therein a rod *b*, screwed throughout its length except over its inner end *c*, which is made non-circular and of smaller diameter than the screwed part of the rod. Alternatively, as shown by Figs. 3 and 4, the hole in the rim may be made of larger diameter than the screw and is not internally screw-threaded. In the felly is secured an internally-screwed bush or nut *n*, through which the screwed rod is passed. It is advantageous to countersink the outer end 45 of the hole through the rim to prevent the burring of the screw-thread, as is shown by Fig. 2, when the projecting end of the rod be-

comes worn down or is withdrawn. In use the end *c* of the rod is first inserted into the hole through the rim and felly from the outside, and it is then rotated until the outer end of the rod is about flush with the surface of the rim. When the driving-wheels commence to slip because of the state of the road or owing to the presence of ice or snow thereon, the rods are screwed outward, so as to project slightly from the rims, by means of a suitable key or spanner fitting upon the ends *c*, so that temporary cogs are thereby produced. When the slippery surface has been passed, the rods may either be turned backward, so that their ends again lie about flush with the rims, or they may be suffered to wear down, since the amount of projections is so small that they cannot damage the roadway. In the latter case the outer ends of the rods will become battered or riveted over; but this is not objectionable. On the contrary the slight head thus formed is a shield for the protection of the screw-thread in the rim. There may be any suitable number of rods in each driving-wheel, but generally as many rods as there are spokes, with which they alternate. The rods, when used as shown by Figs. 1 and 2, serve the additional purpose of strengthening the wheels by insuring a more perfect connection between their rims and fellys.

My improvements may be similarly applied to driving-wheels having rims only without fellys, except that in this case if the nut *n* is used it should be fixed upon or form part of the inner surface of the rim in connection with each of the rods; but the nut will be superfluous when the rims have a sufficient thickness to give a length of internally-screwed hole therein equal to or exceeding the diameter of the screwed rod, as is well understood.

I do not limit myself to the particular formation of the inner ends of the rods, since these may obviously be varied without departing from my invention. For example, the ends may be round and provided with radial "tommy-holes," so that the rods may be turned by a "tommy." Nor is it essential that the rods should be inserted from the outside of the rims, as described, since if their length is not too great they may equally well

be inserted from the inner side. I find it advantageous, however, to make them so long that with wheels having ordinary fellies they must be inserted from the outer side, as this insures a maximum life for them.

What I do claim as my invention, and desire to secure by Letters Patent, is—

In a vehicle-wheel, a rim provided with a plurality of screw-nuts having radial threaded holes, screw-bolts located in said nuts and

adapted to project beyond the rim, said rim having coaxial external countersinks around the ends of the bolts, for the purpose set forth.

In testimony whereof I have signed my name to this specification in the presence of 15 two subscribing witnesses.

HENRY SPURRIER, JR.
